CORWIN C. CHAPMAN, OF PALO ALTO, CALIFORNIA, ASSIGNOR, BY MESNE ASSIGNMENTS, TO FEDERAL TELEGRAPH COMPANY, OF SAN FRANCISCO, CALIFORNIA, A CORPORATION OF CALIFORNIA.

RADIOFREQUENCY ARC CONVERTER AND METHOD OF OPERATING SAME.

Application filed March 24, 1923. Serial No. 627,477.

This invention relates to an arc converter for producing radio frequency oscillations, and more particularly to such a converter in which the arc is maintained in an air-tight chamber containing a hydrocarbon atmosphere.

It is well known that arc converters of this type require an atmosphere of a gas other than air in order to stabilize it and to prevent the arc from breaking at undesired times. An extended period of experimentation on the part of prior observers and inventors led them to specify a hydrogen atmosphere to be the most suitable for this purpose, and this statement has been generally accepted as accurate. I have found, however, that this statement is not universally applicable to all kinds of arcs, although it is still accurate so far as I am able to ascertain, if the statement be limited to arcs in which there is a carbon electrode.

With such arc converters it has been also customary to utilize some form of liquid hydrocarbon, such as an alcohol or kerosene, for forming the atmosphere in the arc chamber, and this has been usually accomplished by supplying the liquid in a regulated drip near to the extremely hot part of the carbon electrode. In such arrangements, it has been understood that the hydrogen constituent of the hydrocarbon is the important element, while the carbon, although not appreciably harmful, is not at all essential. From the good results obtained from the type of arc converters in general use, the term "arc converter" has come to be understood as an arc "operating within an air-tight chamber, in a transverse magnetic field, in an atmosphere of hydrogen and employing a water-cooled copper anode and carbon or graphite cathode", and it has been tacitly assumed that all arc converters may be stabilized in this manner. Arc converters employing longitudinal instead of transverse magnetic fields are not unknown, but they have not been used in actual practice. It is usual with arcs of low power to employ relatively short wave-lengths which correspond to relatively high frequencies. It is well known that for proper operation, the arc must be completely extinguished between each cycle and the arc gap

thoroughly rid of all ionized gases or other conducting or semi-conducting material, the presence of which results from the heat of the arc flame. The higher the frequency, the more rapid must be the scavenging which results from the combined action of the magnetic field and chamber gas. The use of carbon cathodes renders more difficult the proper scavenging on account of the electronic emission from the hot cathode, in addition to that of the arc itself. Even after extinction of the arc the hot cathode will continue to emit electrons, causing the gap to remain partially conductive. These electrons, in addition to those found in the arc flame during the period of ignition, must be removed from the gap before proper operation will result.

In the course of development of a compact arc converter capable of operation on shipboard, and that may consume at full load about one kilowatt of electrical power. I have experimented with arcs utilizing metal such as copper, for both electrodes. In attempting to take advantage of the teachings of prior investigators, I have discovered some important phenomena in connection with the use of metal electrodes that throw considerable further light on the relation between the stability of the arc and the atmosphere within which it operates.

Copper or other metal electrodes are more desirable than carbon, because they may be kept very much cooler, as by the circulation of water through them. The efficiency is thus rendered greater since there is less electronic emission from the cathode, as is the case when carbon or graphic is used, with a consequently more rapid scavenging of the gap between the electrodes during the cyclic extinction of the arc. This results further in the ignition voltage of the arc being sure of attaining its proper value before re-ignition takes place, which promotes the efficiency of the arc considerably. I have found that arc converters employing metal electrodes do not operate in a stable manner and have a tendency to break while signaling, if operated in an atmosphere of pure hydrogen. The same baffling results were obtained when alcohol or kerosene was dripped on the electrodes or fed to the chamber in a vaporized condition. I have been

able to correct this condition by providing an atmosphere for the arc, in a different manner, and it is one of the objects of my invention to make it possible to operate 5 in a stable manner an arc converter having metal electrodes. Although my invention finds its greatest utility in connection with such arcs, it is likewise applicable to arcs utilizing carbon for their cathodes, and thus 10 another object of my invention is to produce an atmosphere for stabilizing the arc, in a novel and efficient manner.

I have found that the important and necessary step in stabilizing the arc when 15 using a complex hydrocarbon such as kerosene or alcohol, is the decomposition or "cracking" of the compound into simpler compounds or indeed into its elements. This is entirely consistent with the observed efficient operation of arcs using a carbon 20 cathode, since in this case the high temperature of the electrode serves immediately to crack the liquid which is dripped upon it. Prior investigators have failed to recognize the importance of this decomposition or 25 "cracking".

In the case of metal electrodes, which are 30 comparatively cool, enough heat may be generated by them eventually to vaporize or partially decompose the hydrocarbon sufficiently 35 to cause the arc to operate as an oscillating arc, but this can only be accomplished by allowing a current greatly in excess of the rated current of the converter to flow for 40 periods of time varying from five to twenty minutes. Even after the arc is brought to an oscillating condition, its operation is unsatisfactory, the radio frequency current unsteady and the arc prone to break at unexpected moments for no apparent reason. In 45 the light of further experiments I conducted in this connection I believe the reason for this unsatisfactory operation has been the insufficient decomposition or "cracking" of the hydrocarbon. I believe that this is a 50 consistent explanation of the failure of arcs using metal electrodes to function properly when attempts are made to operate them in the usual manner.

55 That such arcs fail to function properly even when pure hydrogen is used as an atmosphere I believe is due to the total absence of carbon in the arc chamber. In the ordinary carbon cathode arc, this carbon is very probably supplied from the electrode, but such a source is lacking in an arc using metal electrodes. For this reason, a carbon compound must be used for creating the atmosphere, and furthermore this hydrocarbon 60 must be in the form of relatively simple compounds. What immediate effect the carbon has upon the operation to stabilize it so that it oscillates uniformly and so that it does not break, is not known to me at this time, but 65 I am satisfied that the ultimate effect is that

which I have stated. It is thus another object of my invention to supply cracked or decomposed hydrocarbon compounds to the arc chamber.

In order to disclose still further the difficulties encountered in operating an arc using metal electrodes before the seemingly simple expedient of cracking the hydrocarbon was thought of, some incidents to the attempted operation may be mentioned. With arcs 70 using carbon cathodes, it is a simple matter to rotate the cathode so that the carbon is evenly consumed. With copper electrodes which are kept cool by a circulation of water or other cooling fluid, this rotation is impracticable. In analyzing the reason for the uneven consumption with a view toward its correction, it has been found that the transverse magnetic field bows out the arc 75 between substantially constant spots on the electrode. In order to remedy this condition, it has been suggested that a magnetic field be utilized which has an axis parallel and not transverse to that of the arc electrodes. Demonstrations have shown, in fact, that 80 this expedient causes the arc to travel around the tips, and the uneven consumption is thus remedied. In my investigations to secure a highly efficient arc, I have embodied this longitudinal field in my structures, because 85 it is so essential for the sake of efficiency to provide a cooling circulating fluid to the electrodes. It may also be mentioned that better operating characteristics such as 90 smoothness in running even with low power, are obtained when using longitudinal fields. This is due probably to the great uniformity 95 of such fields in the arc region, which tend to compress instead of elongate the arc. A further explanation of the steady operation 100 of this type of arc employing metal electrodes may be found in the absolutely uniform gas conditions within the arc chamber resulting from the proper "cracking" of the liquid hydrocarbon.

105 That this uniform gaseous atmosphere tends to improve the operation of arcs employing carbon or graphite cathodes is also evident when a study is made of the manner of cracking the hydrocarbon in this case. The liquid hydrocarbon is dripped directly upon the arc flame, which results in an intermittent variation of the temperature of the cathode, as well as of the arc flame itself. A period of time equal in length to many 110 thousands of oscillations is required for the hydrocarbon to become properly decomposed by this process and for the temperature of the arc to return to its normal value. With a properly cracked hydrocarbon, this variation of temperature does not take place. On account of the superior operating characteristics resulting from the use of the longitudinal field, it was thus highly desirable 115 that I avail myself of such a construc- 120

125 130

tion in the ultimate embodiment of a small sized efficient arc for use on shipboard.

Upon attempting to start the oscillations in such a longitudinal field arc by dripping 5 alcohol or kerosene or the like near to the tips of the electrodes, it was found that not sufficient heat was produced to vaporize the compound. At first thought one may attempt to drip the liquid directly on the arc 10 flame itself, but this is entirely impracticable because the flame dodges about and over the active surfaces of the electrodes. It may, of course, be possible after a considerable interval, say of fifteen or thirty minutes, to 15 start the oscillations, but even then it is difficult to predict how long it will remain stable, and it may suddenly break while signaling and without warning. Such performance is evidently highly objectionable 20 and of hardly any use whatsoever.

In the practice of my invention, I make certain that the hydrocarbon is decomposed to the proper degree before it is fed into the arc chamber. I have found that with this 25 simple treatment, the arc may be immediately made to oscillate, and to run smoothly without any tendency to break or to vary the amplitude of the oscillations. Stated in a somewhat different manner, then, 30 an object of my invention is to insure cracking or decomposition of a complex hydrocarbon, either liquid or gaseous, before it is conducted to an arc chamber.

This cracking or decomposition may be 35 accomplished in any well-known manner by the application of a high heat to the compound. However, I prefer to utilize electric energy for this purpose. I have devised a simple and convenient retort or gasifier 40 which employs electricity as the heating agent, and it is thus still another object of my invention to provide a simple and reliable retort of this character.

My invention possesses other advantageous features, some of which, with the foregoing, will be set forth at length in the following description, where I shall outline in full a form of apparatus with which my invention may be practiced, and which I have 50 selected for illustration in the drawings accompanying and forming part of the present specification. Although I have shown in the drawings but one form of the apparatus, I do not desire to be limited thereto, 55 since the invention as defined in the claims may be practiced by other apparatus, and may be embodied in other forms.

Referring to the drawings:

Figure 1 is a diagrammatic view of an arc 60 system embodying my invention; and

Fig. 2 is an enlarged cross-sectional view of the retort or gasifier used in the system shown in Fig. 1.

In Fig. 1 I show the arc chamber 11 in 65 which are placed in operative relation the

two electrodes 12 and 13, which may be made of some metal, such as copper. This arc is adapted to be supplied from a d. c. source, such as the generator 14, which is placed in series relation with the electrodes, as well 70 as with the coil 15. This coil is preferably so arranged with respect to the arc that it exerts a longitudinal field of magnetic force on the arc, and may for this purpose be disposed about one or both of the electrodes 75 12 and 13. A switch 16 may be used for connecting and disconnecting the source 14 from the electrodes, as occasion requires. A radiating circuit such as the antenna 17, inductor 18, and ground 19, may be connected across the arc electrodes so that it may be supplied with oscillatory current produced by the arc. The foregoing description is intended to be quite general, and represents merely one of many well-known arc circuits, with which my invention may be practiced. For this reason, I have made no attempt to set forth any particular means for tuning or for signaling since such arrangements form no part of my present invention. 80

For supplying the arc chamber 11 with an appropriate atmosphere as described hereinbefore, a pipe 20 extends to the chamber 11 and connects therewith. This pipe or inlet is adapted to conduct the decomposed or cracked hydrocarbons from a retort 21 which may be arranged externally of the arc chamber 11. Supply of hydrocarbon, as for example of the liquid form, to this retort is secured from a container 22. Alcohol or kerosene, being low in cost and easily obtainable is the compound ordinarily used for this purpose. This container 22 may be provided with a sight glass 23. The flow of hydrocarbon from the container 22 into the 100 retort is governed by a needle valve 24 which is open only when the arc is in operation. To effect this result, a magnet 25 is provided, the circuit of which is in parallel to the arc, so that it is supplied with current 105 from the source 14 only when the switch 16 is closed. Needle valves and containers having this same general system of control have been utilized heretofore for dripping a hydrocarbon directly into the arc chamber, 110 and it is therefore considered unnecessary to describe these elements in greater detail.

The retort 21, as shown most clearly in Fig. 2, consists preferably of a longitudinally arranged pipe or tube 26 forming the cracking chamber. This tube is arranged to be heated to the desired temperature so as to effect the decomposition, by a convenient source of heat. In the present instance, an electrical heating element 27 disposed helically around the chamber is shown. Between this heating element and the external wall or jacket of the retort there may be placed heat insulating material 28 in order 115 to conserve the heat as well as to maintain 120 125 130

the retort as cool externally as possible. Connections 29 to the heating element extend through the external wall of the retort 21 and may be connected to any appropriate source, such as the generator 14. The top portion 30 of the retort is formed with an inlet 31 which is externally threaded for connecting to the union 32 between the container 22 and the retort 21. The supply pipe 20 leads off from this union. The tube 26 is threaded to the extension 33 on the inside of the top 30. In this way, after liquid drips from container 22 through the union 32 into the retort, and decomposed or cracked in the tube 26, the resultant gas is conducted back through the union 32 and into pipe 20. The tight threaded connection between tube 26 and the extension 33 prevents any leakage of this gas.

There may at times be an accumulation of liquid in the bottom of tube 26, due to an excessive supply of the hydrocarbon, which is ordinarily preferable to an exactly regulated supply. For draining this surplus off, I provide a drain pipe 34 connecting to the bottom of the tube 26, and controlled by a drain cock 35. To prevent liquid that is treated in tube 27 from immediately dropping into the drain, a baffle 36 is placed over the pipe opening within the tube 27. A further purpose of the baffle plate is to cause the hydrocarbon to spatter against the hot interior of the metal tube. It, therefore, reaches the hottest surface in the form of finely divided spray and the instantaneous cracking process is thus furthered by the elimination of the necessity of it cracking a relatively large amount, such as would be represented by a single drop of liquid.

The mode of operation of the apparatus to carry out my invention is evident from the foregoing. The arc when supplied with the decomposed hydrocarbon, may be made to oscillate readily, and the oscillations remain extremely stable under all conditions of signaling. Although I have described an apparatus for cracking complex liquid hydrocarbons, gaseous forms may also be utilized. A smooth running system, hitherto unattainable for long extended periods when metal electrodes are used, is accomplished by the aid of the invention as described.

I claim:

1. In an arc converter, an arc chamber, spaced electrodes disposed in said chamber, and means for supplying a gaseous atmosphere in said chamber including a source of hydrocarbon material, and means remote from said electrodes for decomposing and altering the molecular structure of said material.

2. In an arc converter having a gas tight arc chamber, the process of supplying the arc with a suitable gaseous atmosphere, which comprises decomposing a relatively

complex hydrocarbon compound externally of the arc chamber, and conducting resultant gaseous mixture into the arc chamber.

3. The method of generating an atmosphere for the operation of an arc converter characterized by the use of arc electrodes enclosed in a chamber, and a surface with which a hydrocarbon material may be brought into contact, said method comprising applying heat to said surface from a source other than that developed by the arc and electrodes, and feeding the hydrocarbon material into contact therewith, the temperature of said surface being made sufficiently high to effect decomposition of the hydrocarbon.

4. In an arc converter, an arc chamber, spaced arc electrodes disposed in said chamber, and means for supplying a gaseous atmosphere in said chamber comprising a source of hydrocarbon material, and means including a source of heat other than the heat developed by said arc and electrodes for decomposing said material.

5. In an arc converter, spaced electrodes, a chamber surrounding said electrodes, and means for supplying a suitable atmosphere to the chamber comprising a heated retort for gasifying a hydrocarbon, and means responsive to the supplying of electrical energy to the arc for rendering said retort active.

6. In an arc converter, a pair of arc electrodes, means forming a gas tight chamber about said electrodes, and means for supplying a suitable atmosphere to the chamber, comprising a retort, means for feeding a liquid hydrocarbon into the retort, and means independent of the heat developed by said arc for heating the retort to a degree sufficient to decompose the hydrocarbon.

7. In an arc converter, a pair of electrodes, means forming a gas tight chamber about said electrodes, and means for supplying a suitable atmosphere to the chamber, comprising a heated retort for decomposing a hydrocarbon, and means responsive to the supplying of electrical energy to the arc for rendering said retort active.

8. In an arc converter, a pair of electrodes, means forming a gas tight chamber about said electrodes, and means for supplying a suitable atmosphere to the chamber, comprising a container for a liquid hydrocarbon, an electrically operated valve for the container for permitting it to discharge the liquid, a retort within which the liquid is permitted to drip, and means for heating the retort so that it serves to crack the hydrocarbon.

9. In an arc converter, a pair of electrodes, means forming a gas tight chamber about said electrodes, and means for supplying a suitable atmosphere to the chamber, comprising a container for a liquid hydrocarbon, a

valve for permitting the container to discharge the liquid, said valve being operated in response to the supplying of electrical energy to the arc, and a retort receiving the 5 discharged liquid for decomposing it.

10. In an arc converter, an arc chamber, spaced electrodes disposed in said chamber, and means for supplying an atmosphere for said chamber comprising a heated surface remote from said electrodes, and means for feeding a hydrocarbon compound into contact with said surface, the temperature of said surface being sufficiently high to in-

stantly decompose and alter the molecular structure of said hydrocarbon. 15

11. In an arc converter comprising a pair of spaced metallic electrodes having opposed faces, means comprising a longitudinal magnetic field for causing an arc between said faces to gyrate about the axis of said electrodes, and means remote from said electrodes for supplying an atmosphere of decomposed hydrocarbon gas to said chamber. 20

In testimony whereof, I have hereunto set my hand.

CORWIN C. CHAPMAN.
